UNITED STATES PATENT OFFICE.

HARRY H. LATHAM AND WILLIAM OSTERHOLM, OF CHICAGO, ILLINOIS, ASSIGNEES
TO THE LATHAM MACHINERY COMPANY, OF CHICAGO, ILLINOIS, A CORPORATION
OF ILLINOIS.

WORK-SUPPORTING TABLE FOR WIRE-STITCHING MACHINES.

1,096,113.

Specification of Letters Patent.

Patented May 12, 1914.

Application filed June 5, 1907. Serial No. 377,456.

To all whom it may concern:

Be it known that we, HARRY H. LATHAM and WILLIAM OSTERHOLM, citizens of the United States, residing in Chicago, in the county of Cook and State of Illinois, have invented certain new and useful Improvements in Work-Supporting Tables for Wire-Stitching Machines, of which the following is a specification.

10 This invention relates to improvements in work supporting tables for wire stitching machines and the like, and the primary object of the invention is to provide improved means for raising and lowering the table.

15 A further object is to provide improved means for adjusting the table top with relation to its support and for locking the same in the desired adjusted position according to the nature of the work to be performed.

20 A further object is to provide an improved form of gage for regulating the height to which the table may be adjusted according to the thickness of the work to be performed.

25 A further object is to provide an improved machine of this character which will be simple, cheap and durable in construction, and efficient and effective in operation.

30 To the attainment of these ends and the accomplishment of other new and useful objects, as will appear, the invention consists in the features of novelty in the construction, combination and arrangement of the 35 several parts hereinafter more fully described and claimed, and shown in the accompanying drawings illustrating an exemplification of the invention and in which—

40 Figure 1 is a detail, longitudinal sectional view partly in elevation of an improved table of this character constructed in accordance with the principles of this invention and showing a portion of the supporting standard for the table. Fig. 2 is a detail perspective view of one of the staple clencher members. Fig. 3 is a detail plan view of one of the members for preventing displacement of the adjusting mechanism 45 with relation to its supporting standard. Fig. 4 is a detail perspective view of a portion of the clencher rod. Fig. 5 is a longitudinal sectional view on line 5—5 of Fig. 1. Fig. 6 is a detail perspective view of one of

the supporting arms for the table sections. 55 Fig. 7 is a sectional view on line 7—7 of Fig. 5. Fig. 8 is a view similar to Fig. 7 showing the parts in a different position. Fig. 9 is a sectional view on line 9—9 of Fig. 5. Fig. 10 is an end elevation of the table showing 60 the sections thereof arranged at an angle to each other. Fig. 11 is a detail perspective view of one of the locking rods for the table sections. Fig. 12 is an enlarged detail view of a portion of the table showing the 65 clencher members and clencher rod in an adjusted position to clench the staples. Fig. 13 is a detail perspective view of one of the members of the clencher block. Fig. 14 is a detail perspective view of the other 70 member of the clencher block. Fig. 15 is a detail perspective view of the entire clencher block. Fig. 16 is a detail plan view of the hinged connection of the table sections. Fig. 17 is a detail sectional view of the connection of the table sections, showing the 75 sections arranged at an angle to each other. Fig. 18 is a detail elevation of the operating mechanism for the clencher rod. Fig. 19 is a detail sectional view on line 19—19 of Fig. 80 1. Fig. 20 is a detail sectional view on line 20—20 of Fig. 1.

Referring more particularly to the drawings and in this exemplification of the invention, the numeral 20 designates a suitable support for the table, which is provided with an aperture 21 in which is mounted a vertically adjustable saddle post 22, to the upper end of which is secured a saddle frame 23 and which latter is movable with the saddle post. The saddle post is preferably hollow as at 24 and is preferably provided with a reduced portion 25 adjacent the lower extremity thereof and which is provided with interior screw 95 threads.

A suitable hollow bolt or adjusting screw 26 is preferably provided with a reduced portion 27 having peripheral screw threads thereon, and said bolt or screw projects 100 through the support 20 in such a manner that the threaded extremity 27 thereof will enter the aperture 25 in the saddle post 22 so that the threads thereon will engage the threads in the aperture and the extremity 27 105 of the bolt will enter the aperture 24 so that when the bolt or screw 26 is rotated, the saddle post 22, together with the saddle

frame 23, will be vertically adjusted with relation to the support 20.

The aperture 21 in the support 20 is preferably provided with a reduced portion 28 5 to form a shoulder, against which the saddle post rests when the latter has reached the limit of its adjustment in one direction.

Any suitable means may be provided for holding the screw or bolt 26 against displacement. A suitable and efficient means 10 for accomplishing this purpose comprises a member 29 which is preferably split, as shown more clearly in Fig. 3 of the drawings, and said member is provided with a 15 semi-circular recess 30 in each of the sections thereof so that when the sections are placed together, the recesses will form an aperture through the plate.

The screw or bolt 26 is provided with a 20 recessed or grooved portion 31, the diameter of which is substantially equal to the diameter of the aperture formed by the recesses 30 in the sections of the member 29, so that when the recesses 30 are placed 25 around the reduced portion 31, a portion of the member 29 will extend into the recess of the screw or bolt to form a supporting collar or member therefor, and to permit the screw or bolt to rotate loosely within the aperture formed by the recesses 30. The member 29 may be secured against rotation in 30 any desired or suitable manner, preferably by means of suitable screws or bolts passing through the apertures 32 therein and into 35 the support 20.

The lower extremity of the screw or bolt 26 preferably extends a short distance below the plate or member 29 and secured thereto is a suitable operating wheel or 40 handle 33 by means of which the screw or bolt may be rotated when it is desired to adjust the saddle post.

The screw or bolt 26 is provided with an aperture 34 passing longitudinally there- 45 through and the aperture adjacent the lower extremity thereof is preferably enlarged as at 35. A tubular member 37 is provided with a reduced extremity 38 to form a shoulder 39 and said reduced extremity 38 50 is adapted to enter the enlarged portion 35 of the aperture 34 in the bolt or screw 26 so that the extremity of the bolt or screw 26 will rest upon the shoulder 39 and said member 37 is provided with a bifurcated 55 portion 40. This tubular member 37 is secured to the bolt or screw 26 to hold it against relative rotation in any desired or suitable manner, preferably by connecting the members by a press fit between the re- 60 duced extremity 38 and the enlarged portion 35. A hollow block or member 41 loosely surrounds the bifurcated extremity of the member 37 and projects for some distance beyond said end and is provided with 65 a reduced portion 42 having interior screw

threads therein beyond the extremity of the member 37.

A tubular rod or screw 43 is provided with peripheral screw threads 44 preferably located at a point adjacent one extremity 70 thereof, and said rod or screw is adapted to be inserted into the block or member 41 so that the threaded portion 42 thereof will engage the screw threads in the said member whereby the rod or screw 43 will be supported by the block or member 41. The upper extremity of the rod or screw 43 is adapted to enter the tubular member 37 and the exterior diameter thereof is smaller than the interior diameter of the member 37, so 75 that when the rod or screw 43 is in position, the extremity of the member 37 may freely move between the tubular rod or screw 43 and the member 41, when the saddle post 22 is adjusted.

Secured to the tubular rod or screw 43, preferably at a point adjacent the upper extremity thereof, is a laterally projecting lug or pin 45, which passes through the clencher rod 46 and extends into the bifurcation 40 90 of the member 37 and is adapted to engage the walls of the bifurcation thereof to rotate the tubular rod or screw 43 when the wheel or handle 33 is rotated to adjust the saddle post 22 but to permit the tubular rod or 95 screw 43 to move longitudinally with respect to the member 37.

When the saddle post 22, the hollow bolt or screw 26, the member 37, and the hollow rod or screw 43 are assembled in the manner above described, the apertures passing longitudinally therethrough will be in alignment with each other, and arranged within and passing through these registering apertures is a clencher rod 46. The lower extremity 47 thereof projects beyond the extremity of the tubular rod or screw 43 and is provided with peripheral screw threads 48, and 49 designates a suitable nut adapted to engage the threads 48 on the extremity 47, 110 and said nut is adapted to engage the adjacent extremity of the rod or screw 43 to prevent any strain falling upon the pin 45 due to the tendency of the clencher rod 46 being drawn through the assembled members.

The upper extremity 50 of the clencher rod terminates within the aperture 24 in the saddle post 22 and loosely surrounding said extremity is a member 51, which is secured to the clencher rod 46 in any desired manner 120 to permit said rod to rotate with respect thereto. A suitable and efficient means for accomplishing this purpose comprises a pin 52, which extends through the member 51 and into a suitable circumferential recess or 125 groove 53 in the extremity 50 of the clencher rod 46 to permit the clencher rod 46 to be rotated for the purpose of adjusting the member 51.

Secured to the saddle frame 23 is a 130

clencher block shown more clearly in Fig. 15 of the drawings, and said block preferably comprises two members, 54, 55. The member 54 is provided with an offset or recessed portion 56 intermediate the ends thereof and an upwardly projecting lip or extension 57. The member 55 is also provided with an upwardly projecting lip or extension 58 and is adapted to be secured to the member 54 in such a manner that the lips or extensions 57, 58, will stand adjacent to and be spaced from each other. The member 54 is preferably provided with recessed or shouldered portions 59 against which the extremities of the member 55 are adapted to rest so that the outer face of the member 55 will be substantially flush with the adjacent face of the member 54. The member 55 may be secured in position in any desired or suitable manner, preferably by means of screws or bolts 60.

The lips or extensions 57, 58 are provided with registering apertures 61 and pivotally supported between said lips or extensions 25 are clencher members 62, each of which is provided with a depending arm 63. The clencher block is secured to the saddle frame 23 in such manner that the offset or recessed portion 56 is disposed directly above the extremity of the member 51, and said extremity of the member 51 is provided with lugs or projections 64 adapted to engage the respective arms 63 of the clencher members 62 to rock the same about their points of 30 pivotal support when the member 51 is moved in one direction and to engage the clenchers 62 to move them in an opposite direction when the member 51 is moved in an opposite direction.

40 An arm or lever 65 is pivotally supported intermediate its ends, as at 66, to the support 20 adjacent the block or member 41, and one extremity thereof is adapted to stand between spaced ears or projections 67 on the member 41 and is connected to said block or member, preferably by means of a spring controlled bolt or latch 68, which passes through suitable apertures in the ears or projections 67 and a slot 69 in the adjacent extremity of the arm or lever 65. The bolt or latch 68 is preferably provided with an operating handle 70 by means of which the operator may move the bolt or latch to connect or disconnect the block or member 41 to the extremity of the arm or lever 65 when desired. Any suitable means may be provided for rocking or moving the arm or lever 65 about its point of pivotal support 66, such as a rod or bar 70^a which is 45 mounted for sliding movement in suitable bearings 71 in the support 20. One extremity of the rod or bar is provided with a laterally projecting lug or pin 72 adapted to engage a suitable slot 73 in the free extremity of the arm or lever 65.

Any suitable means may be provided for moving the rod or bar 70^a in the bearing 71. A suitable and efficient means for accomplishing this purpose comprises a shaft 74, secured to which is an operating cam 75 70 adapted to engage the free extremity of the rod or bar 70^a. If desired, a suitable anti-friction roller 76 may be journaled to the extremity of the rod or bar 70^a.

The support 20 is provided with an aperture 77 adjacent the saddle post 22 and a projecting jaw 78 on one side of the aperture. Arranged within the support 20 and adjacent the jaw 78 and the aperture 77 is a key-way 79 which extends longitudinally of the support and mounted in said key-way is a key 80, which is provided with a laterally projecting portion or jaw 81 and said jaw 81 projects through and beyond the aperture 77 and is arranged parallel with the jaw 78 on the support 20 with which it coöperates to form a gage. Any suitable means may be provided for adjusting the jaw 81 with respect to the jaw 78, when the saddle post 22 is moved. A suitable and efficient means for accomplishing this purpose comprises a pin or bolt 82 which passes through a suitable aperture in the key 80 and into the saddle post 22 for locking the key to the saddle post for movement therewith, so that when the saddle post is adjusted by means of the wheel or handle 33, the jaw 81 will be simultaneously adjusted with relation to the jaw 78. The rotation of the wheel or handle 33 will also rotate the tubular member 37 and the tubular rod 43 will be longitudinally adjusted with respect to the block 41 through the medium of the pin 45 and bifurcation 40 in the member 37. As this tubular rod 43 is adjusted, the clencher rod 46 will also be longitudinally adjusted and will rotate axially with respect to the member 51 to permit such adjustment to vary the movement of the clencher rod under the influence of the cam 75.

105 A table, comprising two sections 83 which are hinged together at one edge by a suitable hinge connection 84, said sections being provided with a suitable aperture 85, is arranged above the saddle frame 23 in such a manner that the aperture 85 therein will be located directly above the clencher members 62 to permit the latter to be moved about their point of pivotal support so that the upper faces of the clencher members 110 will stand substantially flush with the top of the table when the latter is in the position shown in Figs. 1 and 10 of the drawings.

115 The saddle frame 23 preferably extends for some distance beyond the sides of the support 20 and arranged adjacent each extremity and on each side of the saddle post are bearings 86, which are respectively arranged to aline with each other, and slidably mounted in the alined bearings are 120 125 130

rods or bars 87 shown more clearly in Fig. 9 of the drawings. The extremities of these rods or bars 87 are connected by a suitable cross bar 88 which latter serves as a handle 5 for simultaneously moving the rods in their respective bearings, and any suitable means may be provided, such as projecting lugs or pins 89 or the like arranged adjacent the free extremities of the rods 87 to prevent 10 the rods from being accidentally displaced and for limiting the longitudinal movement thereof in one direction. Each of these rods 87 is provided with a cut-away or recessed portion 90, shown more clearly in Fig. 15 11 of the drawings, which is located preferably adjacent the bearings 86.

Secured to the sections 83 of the table are arms or brackets 91 which are, preferably struck on an arc, as shown more clearly in 20 Fig. 6 of the drawings, and are provided with depressions or recesses 92, 93, located adjacent the extremities thereof. These arms are secured to the lower face of the respective sections 83 of the table at points adjacent 25 the cut-away or recessed portions 90 of the rods or bars 87 and the free extremities thereof are adapted to pass through suitable apertures 94 in the saddle frame 23 and above the rods or bars 87, so that the 30 rods or bars will form supports for the arms 91 as the latter pass through the recesses 94.

The recesses or cut-away portions 90 in the rods or bars 87 are adapted to be moved into or out of alignment with the recesses 92, 35 93 in the extremities of the arms 91, and when said cut-away or recessed portions are in alignment therewith, the sections 83 of the table may be moved about their points of 40 pivotal support with relation to each other to permit the table sections to assume the position shown in Fig. 10 of the drawings. After the table has been adjusted to this position the rods or bars 87 may be moved to the position shown in full lines in Fig. 9 45 of the drawings to cause the cut-away or recessed portions 90 to be moved away from the arms 91, causing the body of the rod or bar 87 to enter the recess 93 in the arm for locking the table in its adjusted position. 50 When it is desired to adjust the table to the position shown in Fig. 1 of the drawings, the rods or bars 87 may be moved by means of the handle 88 into such a position that the cut-away or recessed portions 90 will 55 be adjacent the edges of the respective arms 91, and when in this position the sections 83 of the table may be moved about their points of pivotal support with relation to each other and into the position shown in Fig. 1. 60 After the table has been thus adjusted, the recesses 92 will be adjacent the recessed or cut-away portions 90 in the rods or bars 87, which latter may be longitudinally moved in the supporting bearings 86 to the position 65 shown in full lines in Fig. 9 of the

drawings, causing the recesses 90 to move out of engagement or register with the recesses 92 allowing the body portion of the rods or bars 87 to enter the recesses 92, as shown in Fig. 7 of the drawings to lock the 70 table sections against movement.

If it is desired to remove the table sections 83 from the saddle frame, the sections may be adjusted to the position as shown in Fig. 1 of the drawings and then by bodily 75 moving or manipulating both of the sections, the arms 91 may be disengaged from the rods or bars 87 and the table top may be readily removed.

This improved construction of table is 80 particularly adapted for use with the construction of stapling and driving mechanism set forth and claimed in an application filed by us June 5, 1907, Serial No. 377,455, and is so arranged that the clencher members 85 62 will be arranged directly under the staple driver so that when the material which is supported by the table is placed under the staple forming and driving mechanism, the ends of the staple as they pass through the 90 material will be engaged and clenched by the clencher members 62.

The jaws 78 and 81 are so adjusted that the distance between them may be the same as the distance between the top of the table 95 and the operative parts of the staple forming and driving mechanism above referred to, thus forming a gage by which the height of the table may be adjusted to the thickness of the work which it is required to fasten. The work is placed between the jaws 78 and 81 and by turning the wheel or handle 33, the saddle post 22 is moved until the distance between the jaws 78 and 81 corresponds to the thickness of the work. The 100 work may be then removed from between the jaws and the staple former will be simultaneously adjusted at a suitable distance from the top of the work supporting table.

With this improved construction of machine, it will be noted that the operation of the clencher rod and clencher members 62 is under the control of the operator, that is, if for any reason the operator desires to arrest the movement of the clencher rod in 115 case of accident or for any other reason, he can disconnect the same from its operating mechanism by simply withdrawing the latch or bolt 68 by means of the operating handle 70. When the block or member 41 is locked 120 to the operating lever 65 and motion is imparted to the latter after the table has been adjusted, the block or member 41 will be moved by said lever and will raise the clencher rod 46 to operate the clencher members 62 in the manner as already set forth.

In order that the invention might be fully understood by those skilled in the art, the details of the foregoing embodiment thereof have been thus specifically described. 130

What we claim as new and desire to secure by Letters Patent is—

1. In combination, a support, a saddle post vertically adjustable with respect to the support, a table supported by the saddle post, said support being provided with a transverse aperture, a fixed jaw on the support, said saddle post being provided with a keyway within its body extending longitudinally of the saddle post and communicating with the aperture, a key disposed within said keyway and provided with a lateral projection extending through the said aperture, said projection being adapted to coöperate with the fixed jaw, and means for adjusting the saddle post and key.
2. In combination, a support, a saddle post vertically adjustable with respect to the support, a table supported by the post, said support being provided with a transverse aperture, a fixed jaw on the support, said saddle post being provided with a keyway communicating with the aperture, said key way being located within the post and extending longitudinally thereof, a key disposed within the keyway and provided with a lateral projection extending through the aperture and coöperating with the fixed jaw, means for securing the key for movement with the saddle post, and means for adjusting the saddle post.
3. In combination, a support, a saddle post vertically adjustable with respect to the support, means for adjusting the post, a table supported by the post, clencher members, a clencher operating member, an adjustable support for said member, a connecting member disposed between the post adjusting means and the clencher operating member support, said member having a sliding connection with the last said support and a non-rotatable engagement with the post adjusting means, whereby the saddle post and the clencher operating member may be moved independently of and with respect to each other, and means for moving the clencher operating member support.
4. In combination, a support, a saddle post vertically adjustable with respect to the support, means for adjusting the post, a table supported by the post, clencher members, a clencher operating member, an adjustable support for said member, a connecting member disposed between the post adjusting means and the clencher operating member support, said member having a sliding connection with the last said support and a non-rotatable engagement with the post adjusting means, whereby the saddle post and the clencher operating member may be moved independently of and with respect to each other, means for moving the clencher operating member support, and a detachable connection between the last said member and its operating means.

5. In combination, a support, a saddle post vertically adjustable with respect to the support, means for adjusting the post, a table supported by the post, clencher members, a clencher operating member, an adjustable support for said member, a connecting member disposed between the post adjusting means and the clencher operating member support, said member having a pin and slot connection with the last said support and a non-rotatable engagement with the post adjusting means, whereby the clencher operating member and the saddle post may be moved independently of and with respect to each other, and means for moving the clencher operating member support.
6. In combination, a support, a saddle post vertically adjustable with respect to the support, a table supported by the post, clencher members, a tubular member for adjusting the post, a clencher operating member, an adjustable tubular support for the clencher operating member, said clencher operating member passing through the said tubular member, a tubular connecting member surrounding the clencher operating member and having a pin and slot connection with the said adjustable tubular support and a non-rotatable engagement with the said tubular member whereby the clencher operating member and said saddle post may be moved independently of each other, and means for moving the clencher operating member.
7. In combination, a table support, a table comprising hinged sections, arms secured to and depending from the sections, and a member movably mounted on the support and adapted to engage the arms to hold the table sections in position, said member being movable transversely with respect to the arms.
8. In combination, a table support, a table comprising hinged sections, arms secured to and depending from the sections, said support being provided with recesses into which the arms are adapted to move, and a member movably mounted on the support and adapted to extend across the recesses to form a support for the arms, and means whereby said member will lock the arms against movement to hold the table in an operative position.
9. In combination, a table support, a table comprising hinged sections, arms secured to and depending from the sections, said support being provided with recesses into which the arms are adapted to move, a member mounted for sliding movement on the support and extending transversely across the recesses, said member being provided with recesses adapted to be moved adjacent the arms to permit the table sections to be adjusted with respect to each other,

said recesses being also adapted to be moved away from the arms to lock the arms against movement to hold the sections in their adjusted position.

5. 10. In combination, a table support, a table comprising hinged sections, arms depending from the sections, said support being provided with spaced bearings, a member slidingly mounted in said bearings, said 10 arms being provided with offset portions adapted to be brought into engagement with the said member to hold the table sections in position, and said member being provided with recesses adapted to be moved ad-

jacent the offset portions of the arms to permit the arms to be moved to adjust the table sections and to be moved away from said portions to lock the arms against movement and to hold the table sections in position. 15

In testimony whereof we have signed our 20 names to this specification, in the presence of two subscribing witnesses, on this 3rd day of June, A. D. 1907.
